(57) **CLAIM**

The ornamental design for a goods display tool, as shown and described.

DESCRIPTION

FIG. 1 is a front view of a goods display tool showing my new design;

FIG. 2 is a top view thereof;

FIG. 3 is a rear view thereof;

FIG. 4 is a bottom view thereof;

FIG. 5 is a right view thereof, the left view thereof being a right-and-left-reversed image;

FIG. 6 is an end view taken through line 6-6 of FIG. 1;

FIG. 7 is a partial enlarged view taken through line 7-7 of FIG. 6; and,

FIG. 8 is a front perspective view thereof.
